United States Patent

Des. 235,238
Patented June 3, 1975

235,238

DISPLAY STAND OR SIMILAR ARTICLE

Melvin Braverman, Glen Cove, N.Y., assignor to A&M Leatherlines, Inc., New York, N.Y.

Filed June 25, 1973, Ser. No. 373,571

Term of patent 14 years

Int. Cl. D20—02

U.S. Cl. D6—85

FIG. 1 is a front elevational view of a display stand or similar article embodying my new design;

FIG. 2 is a plan view thereof; and

FIG. 3 is a side elevational view thereof as indicated by the arrow in FIG. 2.

I claim:

The ornamental design for a display stand or similar article, as shown and described.
